Primary Examiner—Stacia Cadmus

(74) Attorney, Agent, or Firm—Davidson, Davidson & Kappel, LLC

(57) **CLAIM**

The ornamental design for a wheel, as shown and described.

DESCRIPTION

FIG. 1 is a front view of the wheel; and,
FIG. 2 is a front and side perspective view of the wheel.
The bottom and sides of the wheel shown in broken line
form no part of the claimed design thereof.

1 Claim, 2 Drawing Sheets*FIG. 1*

FIG. 2
